United States Patent Office

Des. 213,518
Patented Mar. 11, 1969

213,518

GASLIGHTER

Albertus van Poppel, Asserstraat 11, Rolde, Netherlands

Filed Sept. 11, 1967, Ser. No. 8,537

Term of patent 3½ years

U.S. Cl. D48—27
Int. Cl. D27—05

FIGURE 1 of the drawing is a side elevation of a gaslighter showing my new design;

FIGURE 2 is a bottom elevation of the gaslighter; and

FIGURE 3 is a front elevation thereof.

The dotted line showing of a flame in FIGURE 3 is for illustrative purposes only.

I claim:

The ornamental design for a gaslighter, as shown and described.
